DESIGN FOR REGALIA FOR A FRATERNAL ORGANIZATION

Edwin Robinson Wilmarth, Attleboro Falls, Mass., assignor to Sovereign Grand Lodge of the
I. O. O. F., Baltimore, Md., a corporation of Maryland

Application July 5, 1941, Serial No. 101,914

Term of patent 14 years

To all whom it may concern:

Be it known that I, Edwin Robinson Wilmarth, a citizen of the United States, residing at Attleboro Falls, in the county of Bristol and State of Massachusetts, have invented a new, original, and ornamental Design for Regalia for a Fraternal Organization, of which the following is a specification, reference being had to the accompanying drawing, forming part thereof.

Figure 1 is a view in elevation of regalia showing my new design;

Figure 2 is a side elevational view; and Figure 3 is a bottom view.

I claim:

The ornamental design for regalia for a fraternal organization, substantially as shown.

EDWIN ROBINSON WILMARTH.
